UNITED STATES PATENT OFFICE.

HENRI A. LINDSEY, OF BRANDYWINE HUNDRED, DELAWARE, ASSIGNOR TO E. I. DU PONT DE NEMOURS & COMPANY, OF WILMINGTON, DELAWARE, A CORPORATION OF DELAWARE.

PROCESS OF MAKING DECORATED LEATHER SUBSTITUTE AND THE PRODUCT THEREOF.

Application filed February 24, 1921. Serial No. 447,559.

To all whom it may concern:

Be it known that I, HENRI A. LINDSEY, a citizen of the United States, and a resident of Brandywine Hundred, in the county of New Castle and State of Delaware, have invented a certain new and useful Process of Making Decorated Leather Substitute and the Product Thereof, of which the following is a specification.

- 10 This invention relates to a process of making a decorated leather substitute in the similitude of a patterned woven fabric, and to the article produced by such process. An object of the invention is to provide a process for the convenient and ready production of leather substitute whose pyroxylin coated surface shall closely resemble a woven fabric having decorations, such as flowers or what not, woven therein; it is also an 20 object to provide leather substitute of the character indicated.

Whereas various types of decorated leather substitute have heretofore been produced for various purposes and specific uses, they have 25 more particularly resembled decorated leather, and been more particularly adapted for use in the place of decorated leather. None of them has sufficiently resembled woven fabric, with a pattern incorporated in 30 the weave, to make it a wholly satisfactory substitute for such a patterned fabric in the upholstery of the more decorative type of furniture and the like, where a patterned-fabric appearance, rather than a 35 decorated-leather appearance, is desired. By the present process, there can be produced a leather substitute—or rather a patterned-fabric substitute made of leather substitute—which resembles patterned fabric sufficiently closely to make its use in the place 40 of patterned fabric artistically practical and satisfactory.

In the accompanying drawing I have shown the patterned fabric substitute in its 45 various stages of production, and it will be understood that, due to the limitations of black and white drawing and the necessity for simplicity, but slight attempt at decorative effect, and no attempt at exact showing 50 of the fabric-weave embossing, has been made. Figure 1 is an illustration of the leather substitute before decoration; Figure 2, an illustration of a small portion of substitute after application of the pattern, and

Figure 3, an illustration of the portion 55 shown in Figure 2 after embossing.

In making substitute in accordance with the present process the procedure is preferably as follows:—The leather substitute having been prepared by coating a web of fabric 60 1 on one side with a pyroxylin film 2 in any usual or other satisfactory way, the desired pattern 3, such as flowers, leaves or other design, like, in appearance, the pattern woven in the particular fabric it 65 is desired to imitate, is applied to the pyroxylin face of the web in any suitable way, and the so-decorated face is embossed, as indicated in a conventional and elementary manner by the lining 4, by pressing 70 thereon with an embossing element, as a plate or roll, covered with a fabric having substantially the same general character of weave as the fabric to be imitated. The film is of course colored with incorporated 75 pigment to give the base color of the fabric to be imitated, and the decorations are of the colors of the figures of the fabric.

It is to be particularly noted that the web is embossed with the fabric weave 80 after—not before—the pattern or figures have been applied to the pyroxylin surface. The result is that the whole of the decorated surface of the web has a fabric-like appearance, that is, the figures as well as the plain 85 portions of the surface between the figures have that appearance, and not merely the plain portions. Furthermore, the embossing destroys the glossy appearance of the plain portions and the superposed and 90 glossy appearance of the decorations, and gives the whole surface a uniform character the decorations and the plain portions blending each into the other substantially 95 as a woven pattern blends with its background. The resulting article, then, has substantially the same appearance as the imitated patterned fabric.

The decorations may be applied in any suitable way, for example by painting, by 100 printing, or by indenting the outlines of the pattern in the surface by embossing and then filling the indentations with pigment. It is of course desirable to use a paint containing a high boiling pyroxylin solvent, an 105 ink containing pyroxylin, or pigment in pyroxylin solution, as will be understood by those skilled in the art, the specific type of

paint, or the like, forming no part of the present invention.

As a specific example of making a patterned-fabric substitute in accordance with 5 the process, I may make an imitation of the machine-made "tapestry" used for fine upholstering, by applying the pattern, or figures consisting of conventionalized flowers and leaves, to the completed undecorated 10 leather substitute, doing this by first indenting an outline of the pattern in the pigmented-pyroxylin surface and then applying a thin pigmented pyroxylin solution to the entire surface and scraping the solution 15 from all but the indented figure outlines, and drying the solution remaining in the outlines, all in the well understood manner; and then embossing the entire surface with an embossing element covered with rep, taking 20 care that the embossing is sufficiently deep to substantially obliterate the previously indented figure outlines, leaving the entire surface with its primary characteristic, the imprint of the corded or ribbed 25 surface of the rep. Of course such combinations of colors may be used as desired, and, by way of example, I have found a black pyroxylin surface with blue-green figures pleasing.

30 I claim:—

1. The process of making decorated leather substitute having a patterned-fabric appearance which comprises, applying a pigmented, opaque, web-concealing leather-substitute 35 film to a textile fabric base, decorating said film with figures to pattern the film, as distinguished from decorating the fabric base, and uniformly embossing the entire film,

both the figures and the plain areas therebetween, to represent the weave of a textile 40 fabric.

2. The process of making leather substitute having the appearance of machine-made tapestry which comprises, decorating the already coated face of a leather-substitute, 45 having a film of opaque pigmented pyroxylin, with conventionalized figures characteristic of tapestry and contrasting in color to said film, and uniformly embossing the entire face, both the figures and the plain 50 areas therebetween, to represent the weave of rep.

3. As an article of manufacture, a decorated leather substitute comprising a textile fabric base carrying a pigmented, opaque, 55 web-concealing leather-substitute film, with said film, as distinguished from said base, decorated with figures to pattern the same, and its entire surface, both the figures and the plain areas therebetween, uniformly embossed 60 with textile-fabric-like weave markings.

4. As an article of manufacture, decorated leather substitute, imitative of machine made tapestry, comprising a fabric base carrying an opaque pigmented pyroxylin film, with said film, as distinguished from said base, decorated with conventionalized 65 figures characteristic of tapestry and contrasting in color with said film, and its entire surface, both the figures and the plain areas therebetween, uniformly embossed with 70 rep-like weave markings.

In testimony whereof I affix my signature.

HENRI A. LINDSEY.
